DESIGN FOR A HEEL FOR A SHOE

Frank Lipp, Brooklyn, N. Y.

Application April 30, 1938, Serial No. 76,890

Term of patent 3½ years

To all whom it may concern:

Be it known that I, Frank Lipp, a citizen of the United States of America, residing in Borough of Brooklyn, county of Kings, and State of New York, have invented a new, original, and ornamental Design for a Heel for a Shoe, of which the following is a specification, reference being had to the accompanying drawing, forming part thereof.

Fig. 1 is a side view of a heel for a shoe, showing my new design.

Fig. 2 is a rear view thereof.

Fig. 3 is a bottom plan view.

Fig. 4 is a perspective view.

I claim:

The ornamental design for a heel for a shoe substantially as shown.

FRANK LIPP.
